UNITED STATES PATENT OFFICE.

SIMON KLEIN, OF VIENNA, AUSTRIA-HUNGARY.

INCANDESCENT ELECTRIC LAMP.

1,113,653.

Specification of Letters Patent. Patented Oct. 13, 1914.

Application filed December 16, 1913. Serial No. 807,086.

To all whom it may concern:

Be it known that I, SIMON KLEIN, engineer, a subject of Hungary, residing at Vienna, Austria-Hungary, have invented 5 new and useful Improvements in Incandescent Electric Lamps, of which the following is a specification.

The present invention relates to incandescent electric lamps or filament apparatus 10 for advertising or signaling purposes.

The object of the invention is to arrange letters, words, numerals or signs consisting of filaments within the globes or bulbs of electric lamps so that when the current flows 15 through the lamps only the outlines or figures of the letters or the like come in an incandescent state, while those portions of the filaments connecting them to the leading in wires and serving as girders or binding 20 25 stays between the several portions of the filament-letters or the like remain invisible.

With this object in view the invention consists in the construction, arrangement and combination of the several parts, all as 25 will be hereinafter described.

One form of electric lamp constructed in accordance with this invention and showing the letter "Z" is illustrated in the accompanying drawing, but it is to be understood 30 that all other letters or numerals or signs or even words could as well be arranged within the globe or bulb of the lamp without departing from this invention.

a indicates the globe or bulb which is provided 35 with the ordinary cap *x* and also with a central supporting rod *g* upon which the support of the filament is mounted; the leading in wires *y*, *y'* being brought in through the glass in the ordinary way and 40 connected with the filament.

The support *b*, *c*, *d*, *e* of the filament *k* consists of a glass rod or the like having the figure of letter Z or any other letter, sign or word to be displayed. Said support 45 is connected to the central supporting rod *g* by one or a plurality of stays *f*. The support *b*, *c*, *d*, *e* may also be formed of a series of short rods of glass or other suitable insulating material melted together.

o, *n*, *m*, *l*, *i* indicate hooks or supports of suitable material firmly secured to the corners and free ends of the glass rod *b*, *c*, *d*, *e*, advantageously by melting the same into the rod. The free ends of the leading in 55 wires *y*, *y'* are crooked at *h* and *p*. The filament *k* of any known variety is wound

on the oppositely directed hooks *h*, *i* in several contacting coils *s*, passes over the hooks *l*, *m*, *n*, *o* along the shanks *e*, *d*, *c*, *b* of the glass rod following the outlines of the Z-shaped support and is finally wound on the hooks *o*, *p* in several close coils *r*. 60

The electric current will pass through the filament *k*, thus heating the same, but since the current is short circuited at the contact 65 points of the coils *s*, *r* wound on the hooks *i*, *h* and *o*, *p* there will be only a low temperature in said coils, which at a given voltage, is not sufficient to heat the coils to a state of incandescence. Thus, the coils 70 *s*, *r* connecting the conducting wires *y*, *y'* with that portion of the filament which follows the outlines of the Z-shaped glass rod and is heated to an incandescent state, will remain dark and unvisible. 75

Each lamp may be provided with a plurality of filaments and with a suitably arranged resistance device in order to enable the regulation for a given voltage.

It is selfevident that instead of said coils, 80 conducting wires of larger cross section than the filament *k* being in contact with the latter could be used and that instead of two coils *s*, *r* or conducting wires, a plurality of same may be employed if the figure of the 85 letter, numeral, sign or word to be brought in an incandescent state requires a plurality of not-incandescent connections between the incandescent portions of said filament.

A series of electric lamps which are furnished with different incandescent letters or the like could be arranged side by side in order to be enabled to obtain compound effects. In this event the lamps are arranged advantageously in series and under the control 90 of only one resistance device. 95

Having now described my invention and in what manner the same is to be performed, what I claim and desire to secure by Letters Patent is:

1. In an advertising or signaling device, in combination with a bulb, a non-conductive support disposed within the bulb and having the outline of a distinctive symbol, and a filament following the contour of the 105 support and being secured thereto whereby said support acts to hold the filament so that the latter during incandescence gives the complete effect of the symbol and whereby the support acts also to itself provide a symbol which is visible in daylight. 110
2. In an advertising or signaling device,

in combination, with a bulb, a glass support within the bulb having the outline of a distinctive symbol, a series of holding elements on the support, and a filament following the contour of the support and connected to said holding elements whereby said support acts to hold the filament so that the latter during incandescence gives the complete effect of the symbol and whereby the

support acts also to itself provide a symbol 10 which is visible in daylight.

In testimony whereof I affix my signature in the presence of two witnesses.

SIMON KLEIN.
